ATTORNEY

UNITED STATES PATENT OFFICE

HEINRICH EBERHARD, OF BERLIN, GERMANY, ASSIGNOR TO RADIO CORPORATION OF AMERICA, A CORPORATION OF DELAWARE

PIEZOELECTRIC FREQUENCY METER

Application filed November 2, 1926, Serial No. 145,865, and in Germany December 29, 1925.

According to a suggestion of Professor Giebe it is possible to reveal or make perceptible by a luminous action the mechanical oscillations of natural period of piezoelectric crystals which are produced by high frequency electric oscillations. This method is very convenient in use and manipulation. However, it is necessary to observe a certain amount of care for the reason that, if 10 the electric stimulus is unduly intense, this is liable to occasion cracking of the quartz crystal.

Now, according to this invention the potential amplitude impressed on and applied 15 to the oscillating crystal is automatically limited by that a glow-discharge lamp or some other means responsive to potential is disposed in parallel to the said crystal. For instance, glow-discharge (or glim-) 20 lamps with a filling of helium and neon, with a slight addition of mercury vapor, exhibit the property of responding to potentials below 100 volts which potentials cause them to flash up. With other gases and 25 with special dispositions of the electrodes, both substantially lower as well as high voltages at which the lamp will react, can be attained. Hence, the responding potential of the parallel-connected voltage-limiting means can be adjusted and adapted to 30 fulfill the admissible or desirable conditions under which the crystal is to work quite ad libitum.

The manner of carrying out this invention will readily be understood from the following description taken in connection with the accompanying drawing in which:

The single figure is a diagrammatic showing of a system embodying the invention. 40 If a glow-discharge lamp is used for the purpose before stated this allows of realizing an additional advantage; for, as shown in the figure the parallel combination of the oscillating crystal K and the glow-discharge lamp G is connected with the terminals of a resonance or tuning circuit R which is excited from a transmitter S, if the coupling is first chosen rather tight, and if the circuit R is approximately set to resonance, the glow-discharge lamp G will

first be caused to light up. This is a convenient sign and indication that the sender is tuned approximately to the correct wavelength. Of course, the resonance circuit R is adjusted roughly to the desired wave for 55 this purpose, alteration of frequency being effected at the transmitter S. Now, if after the glow-discharge lamp G has flashed the coupling between S and R is loosened somewhat, and if the frequency of S is 60 varied in very fine steps, a point will be found where the crystal K begins to oscillate and where it thus deprives the lamp G of energy. Arrangements may then be made in such a way that the lamp G becomes dark, 65 while the oscillating crystal K which, according to Professor Giebe is confined within a rarefied air space (gas space), starts to luminesce instead. In this manner lamp G affords not only protection, but it acts at 70 the same time as a rough indicator of the resonance point.

In the event that several crystals K are used, it is possible to employ a single glow-discharge lamp G as a safety device and 75 as a rough wave-length indicator for all of these different frequencies. The lamp G is most suitably disposed in close contiguity to the luminous tube in which the oscillating crystal is mounted so that both luminous actions can be conveniently observed simultaneously. 80

I claim as my invention:

1. In combination, a first circuit, a tuned circuit including means to vary the tuning of the same, a glow discharge device connected in said tuned circuit and adapted to indicate the transfer of electrical energy from said first circuit to said tuned circuit as the tuning of said tuned circuit is varied, 85 and means connected in said tuned circuit to indicate the condition of resonance between said tuned circuit and the current flowing in said first circuit and simultaneously to render said indicating means inoperative. 90

2. In combination, a first circuit, a tuned circuit coupled thereto, means to vary the tuning of said last mentioned circuit, means to indicate the approximate condition of 95 resonance between said tuned circuit and 100

the current flowing in said first circuit, and means to indicate substantially the exact condition of resonance between said tuned circuit and the current flowing in said first circuit, said last mentioned means when functioning to indicate the condition of resonance serving also to render said first mentioned indicating means inoperative.

3. In combination, a first circuit, a tuned circuit coupled thereto, means to vary the tuning of said last mentioned circuit, a glow discharge device connected in said tuned circuit and adapted to indicate the transfer of electrical energy from said first circuit to said tuned circuit, and a piezo-electric resonator connected in parallel to said glow discharge device, said piezo-electric resonator having a natural period of vibration which will react upon the tuned circuit substantially only when the condition of resonance between said tuned circuit and the current flowing in said first circuit is reached and whereby said piezo-electric resonator renders the glow-discharge device inoperative substantially at resonance of said two circuits.

4. In combination, a primary circuit, a secondary circuit, means connected in said secondary circuit to indicate the transfer of energy from said primary to said secondary circuit when said circuits are tightly coupled, means to vary the coupling of said circuits, and a piezo-electric means to indicate the transfer of energy from said primary circuit to said secondary circuit when said circuits are loosely coupled together, said piezo-electric means reacting upon said first mentioned indicating means to render the same inactive when the natural period of vibration of said piezo-electric means is substantially in resonance with the current flowing in said primary circuit.

5. In combination, a primary circuit, a secondary circuit, means connected in said secondary circuit to indicate roughly the condition of resonance between said circuits, and means to indicate substantially exactly the condition of resonance between said primary and said secondary circuits, said last mentioned means when indicating, being operative to render said first mentioned indicating means inoperative.

6. A wave meter comprising in combination, an alternating current circuit having a coupling coil for coupling said circuit to the source of alternating current to be tested, a glow discharge device connected in said circuit, and a piezo-electric device coupled to said circuit, said glow-lamp being energized by energy transferred from said source to said circuit, said piezo-electric device reacting upon said circuit when the natural period of said device is in resonance with the frequency of energy trans-

ferred from said source to said circuit to de-energize said glow discharge device.

7. A wave meter comprising in combination, an alternating current circuit having a coupling coil, whereby said circuit may be coupled to a source of alternating current to be tested, a piezo-electric device having a predetermined natural period of vibration connected in said circuit, and a glow discharge device connected across said device, said glow discharge device being energized by the energy transferred from said source to said circuit, and said piezo-electric device reacting upon said circuit when the natural period of said device is in resonance with the frequency of energy transferred from said source to said circuit and said piezo-electric device reacting upon said glow discharge device at said condition of resonance to de-energize the same.
